CLAIM

The ornamental design for an automatic barrier gate housing, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front top right side perspective view for an automatic barrier gate housing, showing my new design, with gate arm in closed position;

FIG. 2 is a front top left side perspective view of FIG. 1 thereof;

FIG. 3 is a rear top left side perspective view of FIG. 1 thereof;

FIG. 4 is a top left side perspective view of FIG. 1 thereof;

FIG. 5 is a top right side perspective view of FIG. 1 thereof;

FIG. 6 is a front top right side perspective view of FIG. 1 thereof, with the gate arm in open position; and,

FIG. 7 is a rear top right side perspective view of FIG. 6 thereof.

The broken lines are the unclaimed portions of the automatic barrier gate housing.

The break lines shown in FIGS. 1-7 have been included in order to show the design at a large scale and the design is understood to continue uniformly between the break lines.
